UNITED STATES PATENT OFFICE.

FRANKLIN G. NEUBERTH, OF ANSONIA, AND ERNEST MYRON GRILLEY, OF WATERBURY, CONNECTICUT, ASSIGNEES TO THE WATERBURY JEWEL COMPANY, OF WATERBURY, CONNECTICUT, A CORPORATION.

PIPE-COVER.

1,312,042.

Specification of Letters Patent. Patented Aug. 5, 1919.

Application filed April 4, 1919. Serial No. 287,645.

To all whom it may concern:

Be it known that we, FRANKLIN GEORGE NEUBERTH and ERNEST MYRON GRILLEY, citizens of the United States, residing said 5 5 NEUBERTH at Ansonia and said GRILLEY at Waterbury, county of New Haven, and State of Connecticut, have invented certain new and useful Improvements in Pipe-Covers, of which the following is a specification.

Our invention relates to improvements in pipe covers for smokers' pipes, and the object of our improvement is to produce a cover structure in which the cover proper 10 is mounted so that it may be readily swung back and forth between the position of use or closed position and the open position, without being moved bodily as a whole relatively to the bowl of the pipe, and which 15 has spring means for being held in either the open or closed position, as desired, and which, furthermore, is adapted, without change, for use with pipes of different sizes, both as to the dimensions of the bowl and 20 the thickness of the wall.

In the accompanying drawing:

Figure 1 is a side elevation of a smoker's pipe that is provided with one of our improved pipe covers.

Fig. 2 is a plan view of the pipe cover structure.

Fig. 3 is a rear elevation of the same.

Fig. 4 is a plan view of the blank for the cover.

Fig. 5 is an elevation of the spring structure showing the parts opened out so as to be positioned substantially in one plane.

Fig. 6 is a view corresponding to Fig. 1 showing a pipe provided with a pipe cover 40 of different form from that shown in the figure mentioned.

Fig. 7 is a plan view of the cover structure shown in Fig. 6.

Fig. 8 is a rear elevation of the same.

Fig. 9 is a plan view of the cover of the modified form.

Fig. 10 is an opened out view of the modified form of the spring.

Our improved pipe cover structure comprises a cover proper 10 of suitable size and form to fit over and cover the opening of the bowl 11 of the pipe 12 with which it is to be used and also comprises a spring

structure 13 of peculiar and special form that serves to hold the pipe cover structure 55 in operative position on the said bowl 11 and also serves as spring means for resiliently holding the said cover proper 10 in whatever position it may be set, particularly, to hold the cover proper in either 60 the open or the closed position.

The cover proper 10 comprises a circular body portion 14 that is composed of a flat rim portion 15 that fits over the top wall of the bowl 11 and a middle portion 16 of 65 convex form that is provided with a plurality of vent holes 17. On the front side the rim 15 is bent upwardly to provide a tip 18 that serves as a handle for convenience in opening the cover.

On the rear side, opposite the handle 18, the material of the rim 15 is extended rearwardly in the form of a tail that is composed of the connecting neck 19 adjacent the rim 15; a pair of pintles 20 that extend laterally from the edges of outer end portion of the neck 19, one on each side and opposite one to the other; and a short tail or wing 21 extending outwardly from the pintles 20 and of substantially the same 80 width as the connecting neck 19.

A pair of radial corrugations 22 are provided extending across the rim 15, positioned one on each side of the portion of the rim 15 to which the neck 19 is connected, which serve to provide grooves on the under side of the rim 15 for housing portions of the spring structure 13.

The cover 10 is preferably made of sheet steel.

The pintles 20 serve as the bearing members for the cover 10, being operatively housed in the circular loop portions 23 of the spring structure 13. The wing 21 serves in coöperation with the loops 23 as the positioning means for the cover 10 by having its lateral edge portions in bearing engagement with the material of the said loops 23.

The spring structure 13 is a symmetrical structure, formed of a single piece of wire 100 as follows:—The end portions 24 are in the form of dependent arms, suitable for extending downwardly within the bowl 11 and serving as spring arms in bearing engagement with the inner face of the side wall 105 of the said bowl 11; the middle portion 25

is in the form of a dependent arm of U-shape, suitable for engaging with the outer face of the side wall of the bowl 11 and co-operating with the arms 24 for holding the 5 cover structure in position on the pipe.

At the upper end of each of the individual spring arms 24 is a rearwardly directed bar 26 that extends radially across the top edge of the side wall of the bowl 11, the two bars 10 26 being in registration with the grooves of the corrugations 22 when the cover 10 is in closed position and thereby serving to position the cover 10 relatively to the spring structure 13.

15 Intermediate the rear ends of the cross bars 26 and the individual side arms 27 of the outer clamping arm 25 are the circular loops 23, already mentioned, being upwardly directed relatively to the cross bars 26, and 20 in spaced relation.

25 The material of the spring structure 13 is set so that the bearing loops 23 rub against the edges of the wing 21 and thereby serve as means for resiliently holding the cover 25 in any position in which it may be set.

30 In the modified form of structure shown in Fig. 6 there is provided a snap movement, whereby the cover 10^a is held resiliently and positively in either the open or the closed position, no provision being made for holding in intermediate positions, and in the following manner:

35 The cover 10^a differs from the cover 10 already described in the omission of the friction tail or wing 21, and in lieu thereof there is provided a spring member 28 for frictionally bearing against the part 29 of the neck 19 that is positioned between the pintles 20, the parts being constructed and 40 arranged so that the cover 10^a is resiliently held either in the closed position or the open position as the case may be.

45 As shown, the spring member 28 is integral with the wire of the spring structure 13^a constituting the middle portion thereof, being in the form of a return bend. Thus the outer portion of the spring structure 13^a is generally of W-shape, comprising two individual and relatively narrow U-shaped 50 and downwardly directed clamping arms 25^a for engaging with the side wall of the bowl 11, and the relatively narrow, upwardly directed spring arm 28, also of U-shape.

The spring structures 13 and 13^a both provide a pair of bearings for the cover, 55 resilient supporting means for engaging with the wall of the pipe bowl, and resilient positioning means for positioning the cover in different positions.

The particular structure described is a 60 cover for a smoker's pipe. A structure made on similar lines and involving similar principles of operation, with a proper change in dimensions of the parts may be used for other purposes, as, for instance, for a cover 65 for milk bottles and the like.

We claim as our invention:—

1. In a pipe cover structure, a cover proper and a supporting device therefor, and the said supporting device being in the form of 70 a single piece of wire, the parts being constructed and arranged so that the said piece of wire serves to provide a pair of bearings for the cover, to provide spring clamping arms for engaging with the side wall of the 75 bowl of a pipe, and also to provide means for resiliently positioning the said cover relatively to the supporting device.

2. In combination, a receptacle having side walls bordering an opening and a cover 80 structure for covering the said opening, the said cover structure comprising a cover proper and a supporting device therefor, the said supporting device being in the form of a single piece of wire that is formed so as to 85 provide a pair of bearings for the said cover proper, spring clamping arms for engaging with the said side walls, and also means for resiliently engaging with the said cover proper for positioning thereof in different 90 positions.

3. A pipe cover structure comprising a cover structure formed of sheet material and a frame structure formed of wire, the said cover structure comprising in one piece a 95 cover proper, an extension at the rear thereof, and a pair of pintles on the said extension, the said frame structure comprising a pair of bearings for the said pintles, a pair of spring arms for engaging with a supporting wall, and spring positioning means for engaging with the said extension, and the said wire of which the frame structure is formed being in the form of a single piece. 100

FRANKLIN G. NEUBERTH.
